UNITED STATES PATENT OFFICE

169,128

BAR STOOL

Charles R. Corder, San Diego, Calif.

Application December 26, 1952, Serial No. 22,887

Term of patent 14 years

(Cl. D15—8)

To all whom it may concern:

Be it known that I, Charles R. Corder, a citizen of the United States, residing at San Diego, in the county of San Diego and State of California, have invented a new, original, and ornamental Design for a Bar Stool, of which the following is a specification, reference being had to the accompanying drawing, forming part thereof, in which,

Fig. 2 is a rear end elevational view of the bar stool shown in Fig. 1.

I claim:

The ornamental design for a bar stool, as shown.

CHARLES R. CORDER.
